(57) **CLAIM**

The ornamental design for a travel massage board with massage heads, as shown and described.

DESCRIPTION

FIG. 1 is a top, perspective view of a travel massage board with massage heads;

FIG. 2 is a front, elevation view thereof;

FIG. 3 is a back, elevation view thereof;

FIG. 4 is a right, elevation view thereof;

FIG. 5 is a left, elevation view thereof;

FIG. 6 is a top plan view thereof; and,

FIG. 7 is a bottom plan view thereof.

The dot-dashed broken line in FIGS. 1 and 6 depicts the boundary of the claimed design. The dot-dashed broken line forms no part of the claimed design. The evenly spaced broken lines shown in the drawings illustrate portions of the travel massage board with massage heads that form no part of the claimed design.
